UNITED STATES PATENT OFFICE

167,131

ENDLESS FLEXIBLE ELEMENT CONVEYER

Charles N. Bebinger, New Philadelphia, Ohio, assignor to Joy Manufacturing Company, Pittsburgh, Pa., a corporation of Pennsylvania

Application May 10, 1951, Serial No. 15,131

Term of patent 14 years

(Cl. D55—1)

To all whom it may concern:

Be it known that I, Charles N. Bebinger, a citizen of the United States, residing at New Philadelphia, State of Ohio, have invented a new, original, and ornamental Design for an Endless Flexible Element Conveyor, of which the following is a specification, reference being had to the accompanying drawings, forming a part hereof.

Fig. 1 is a perspective view taken from one side of an endless flexible element conveyor, embodying my new design.

Fig. 2 is an end view in perspective as seen from the discharge end and from the side opposite to that shown in Fig. 1.

Fig. 3 is an end view in perspective from the opposite end to that shown in Fig. 2, but from the same side; and

Fig. 4 is a view in perspective as seen from the discharge end.

I claim:

The ornamental design for an endless flexible element conveyor, as shown.

CHARLES N. BEBINGER.
